CLAIM

The ornamental design of indicia for a shaving razor package, as shown and described.

DESCRIPTION

FIG. 1 is a perspective view of indicia for a shaving razor package showing our new design;

FIG. 2 is a top plan view thereof;

FIG. 3 is a bottom view thereof;

FIG. 4 is a front view thereof;

FIG. 5 is a rear view thereof;

FIG. 6 is a left view thereof; and,

FIG. 7 is a right view thereof.

The broken line showing of a shaving razor package is included for the purpose of illustrating environmental structure and forms no part of the claimed design.
